UNITED STATES PATENT OFFICE.

ELMER R. CORWIN, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONY.

1,141,937.

Specification of Letters Patent.

Patented June 8, 1915.

Application filed April 5, 1913. Serial No. 759,021.

To all whom it may concern:

Be it known that I, ELMER R. CORWIN, citizen of the United States, residing at Chicago, in the county of Cook and State of Illinois, have invented a certain new and useful Improvement in Telephony, of which the following is a full, clear, concise, and exact description, reference being had to the accompanying drawings, forming a part of this specification.

My invention relates to telephone exchange systems employing electro-magnetic switching devices for extending calling lines and has a number of objects and advantages.

My invention has for one of its objects the provision of means whereby link connectors that are to be serially connected with calling lines in establishing telephonic connections will be so related to the calling line extending switching devices at calling stations that these latter devices can only operate to cause the addition of succeeding extensions to preceding extensions when such preceding extensions have been connected with calling lines.

My invention has for another of its objects the provision of means whereby calling line extensions which have been brought to the presence of desired lines may remain in such presence, if the desired lines are previously busy, until the desired lines are free from their previous service and are restored to normal as, for example, in the case of desired subscribers' stations which were previously called or had previously called, such stations being immediately connected with calling lines when through with their previous connections.

My invention has for its further object the employment of primary master switches in seeking relation with calling lines and secondary master switches in relation to different sets of line extensions in combination with switching devices for connecting line extensions with calling lines brought into co-operative relation with the calling lines by said primary and secondary master switches, these secondary master switches pertaining to different groups of line extensions and each common to the extensions of its group.

My invention has other objects and advantages and will be fully explained by reference to the accompanying drawings showing

the preferred embodiment thereof and in which—

Figures 1, 2 and 3, taken collectively and in numerical order with the conductors at the side margins thereof in alinement, illustrate an automatic telephone exchange system arranged in accordance with the invention.

I have shown two substations 300 and 301 having telephone lines extending from substations to an exchange. The equipment at 65 each of these telephone substations includes a telephone switch hook 1, a call bell 2, a condenser 3, a telephone receiver 4 and a telephone transmitter 5, the switch hook having a normal contact serving to connect 70 the signal bell 2 and the condenser 3 in bridge of its associate telephone line and having an alternate contact serving, when the telephone receiver is timely removed, to include such receiver and transmitter 5 in 75 another bridge of the telephone line, the telephone bridge serving to permit of the passage of direct current while the bell bridge serves to prevent such passage.

One side of each telephone line includes as 80 many circuit closing and interrupting switch arms 6, 7, 8 and 9 as there are successive extensions to be applied to calling lines, the switches 6, 7 and 8 serving to effect the operation of the first, second and third selectors 85 while the switch 9 serves to effect the operation of a connector, these switches operating in succession to effect connection between calling and called lines. The switch arms 6, 7, 8 and 9 are carried by ratchet wheels 10, 90 11, 12 and 13 that normally occupy predetermined positions by means of coiled springs in order that one of the telephone line sides may be completed through the switch arms 6, 7, 8 and 9. The switch arms 95 6, 7, 8 and 9 may be moved from their line closing positions into engagement with those contacts in their complementary sets of contacts 14, 15, 16 and 17 that correspond respectively to the groups of thousands, groups 100 of hundreds, groups of tens, and the units that correspond to the number of the desired line and, in the system shown, the sets of contacts 14—17 each includes ten contact points, adjacent contacts being sufficiently 105 separated so that the circuit controlled by each switch arm will be opened as said switch arm moves from one contact to an-

other when being restored to its normal position. Each of the ratchet wheels 10, 11, 12 and 13 has a magnet and spring controlled detent 18, 19, 20 and 21 which are pulled upon by springs to hold their associate ratchet wheels in the positions to which they are rotatably adjusted by the movements of the switch arms carried by the ratchet wheels until such detents are released by the operation of magnets 22, 23, 24 and 25. The switch arms 6, 7, 8 and 9 are moved in counter clockwise directions from their normal positions in setting up the number of a desired line while the associate telephone receiver 4 is upon its switch hook whereupon the said receiver is removed whereupon the magnet 22 is first to operate to attract the detent 18 and release it from engagement with the associate ratchet wheel 10 whereupon the switch arm 6 is moved in a clockwise direction toward its normal position, this detent carrying a stop 26 which is engaged by the arm 6 when this arm engages the contact button of the set 14 next adjacent the contact button engaged by said switch arm when in normal position. By this arrangement the magnet 22, which is designed sluggishly to release its detent 18 to prevent its operation while the arm 6 is passing from point to point, is given sufficient time within which to release its detent 18 whereupon the stop 26 is drawn into register with a recess in the arm 6 to permit this arm to assume its final position, in which position the line circuit is extended to the next arm 7 whereafter the magnet 23, the detent 19, and the stop 27 operate similarly to the magnet 22, the detent, and the stop 28 finally to permit the arm 7 to assume its normal position whereupon the line circuit is extended to the switch arm 8 whereafter the magnet 24, the detent 20 and the stop 28 operate similarly to the corresponding parts associated with the arms 6 and 7 whereby the arm 8 is extended into connection with the arm 9. Thus the magnet 22 is individual to the calling line extending switching device having the arm 7, the magnet 23 is individual to the calling line extending switching device having the arm 8, and the magnet 24 is individual to the calling line extending switching device having the arm 9, inasmuch as the magnets 22, 23 and 24 operate, preferably though not necessarily in the manner described, respectively to bring the arms 7, 8 and 9 into the line circuit. The magnet 25 is now in circuit relation to permit the arm 9 to be restored to its normal position whereupon the telephone bridge at the calling station where the arms 6, 7, 8 and 9 have been adjusted into engagement with their proper buttons for the purpose of calling the desired line is finally complete. By the means illustrated the second and third selector switches and the connector switch are not

set into operation until the link connector in the thousands group has been selected, the third selector and connector switches are not set into operation until the link connector in the hundreds group has been selected and the connector switch is not operated until the link connector in the tens group has been selected. The equipments in association with the arms 6, 7, 8 and 9 are similar with the exception that the detent 21 is not mechanically connected with any stop and the corresponding arm 9 is, of course, not provided with any stop receiving recess. The calling subscriber having removed his telephone from its switch hook after he has set up the number of the desired line by means of the switch arms 6, 7, 8 and 9, will cause a series of operations which will now be described.

A circuit is initially established which is traceable from the grounded battery 29, through the relay 30, the switch hook, telephone transmitter and receiver at the calling station, the sluggishly operating magnet 22, the arm 6 and the button to which it was brought by the calling subscriber, the lower armature switch of the relay 30 and the left hand normal follow up contact of this armature switch, the resistance 31, of preferably five thousand ohms, to the common grounded relay 32. The magnet 22 will not operate through the resistance 31, the operation of this magnet being deferred until the first link connector has been connected with the calling line. The relay 30 also will not operate through the resistance 31, the operation of this relay occurring when the magnet 22 is operated. The resistance of the elements 22, 23, 24, 25 and 30 is desirably two hundred fifty ohms each. The resistance of the relay 32 is desirably one ohm while the battery 29 is of fifty volts. The relay 32 will thus be energized when included in the circuit that has been traced. The left hand armature switch of the energized relay 32 establishes a circuit traceable from the grounded battery 29, through the interrupter 33, the left hand armature switch of the relay 32 and its then engaged contact, the left hand armature switch of relay 34 and its contact, the wiper 35 of the master switch, the waiting contact 36 with which its wipers happen to be in engagement, the motor magnet 37, the normal contact of the intermediate armature switch of relay 38, this armature switch, to ground. It should be stated in passing that the master switch that includes the wiper 35 also has additional wipers 39, 40, 41, 42 and 43 which are adapted for engagement with waiting contacts 44, 45, 46, 47 and 48, these waiting contacts together with the waiting contact 36 being individual to the motor magnet 37, there being as many of these motor magnets as there are sets of such waiting contacts, said wipers normally resting in engagement with 130

some such set of waiting contacts and being moved from engagement with such set of waiting contacts into engagement with another set of such waiting contacts that are individual to another and unemployed motor 37 when the master switch has performed its function in coöperation with the motor magnet 37 with which it was first associated in extending a calling telephone line. Each 10 motor magnet 37 is individual to a link connector which is first to become connected with a calling line, these connectors being connected with calling lines before the link connectors in the thousands groups are connected with the calling lines, the link connectors in the thousands groups being connected with the calling lines through the intermediation of the former link connectors. Each link connector to which a motor magnet 37 is individual includes traveling portions 20 which are shown in the form of wipers 49, 50 and 51, these wipers being carried by a ratchet wheel 52 which is operated by the motor magnet 37 as this motor magnet is intermittently energized due to the action of the interrupter 33. The link connectors having the wipers 49, 50 and 51 are divided into the same groups into which the motor magnets 37 are divided so that the master switch 30 having the wipers 35, etc., are common not only to the motor magnets 37 of a group but also to the group of link connectors having this group of motor magnets. The motor magnet 37 will continue in operation until the wipers 35, 40 and 51 have engaged the waiting contacts 53, 54 and 55 pertaining to the calling line, these wipers traveling over a plurality of sets of these waiting contacts in seeking a calling line, each of such sets pertaining to an individual subscriber's line. Similarly positioned waiting contacts of the different lines are in multiple connection in the different switches. When the wipers 49, 50 and 51 have encountered the waiting contacts 53, 54 and 55 of a calling line a circuit is established traceable from the grounded battery 29, through the relay 30, one side of the telephone line, the telephone receiver and transmitter at the calling station, the magnet 22, the switch arm 6 and the button upon which this switch arm is resting, the other side of the calling line, the lower armature switch of relay 30 and its right hand normal follow-up contact, the waiting contact 55, the 50 wiper 51 engaging the same, the waiting contact 44, the wiper 39 then engaging the same, the left hand winding of relay 34, the right hand armature switch of relay 32 and its then engaged contact, to ground. The 55 circuit just traced does not include the resistance 31 and as the resistance of the left hand coil of the relay 34 is of one hundred ohms, current from the battery 29 is permitted to flow in sufficient volume to energize 60 the relay 30 whose armature switches are attracted, the lower armature switch leaving its normal follow-up contacts and engaging its alternate contact, the waiting contact 54 being thus connected with one side of the calling telephone line, the waiting contact 53 being permanently connected with the other side of such line. As the circuit just traced includes the relay 34, the left hand armature switch of this relay opens the circuit of the motor magnet 37 whose wipers 70 have encountered the waiting contacts of the calling line whereby these wipers remain in connection with such waiting contacts. The relay 34 being energized, a locking circuit is established traceable from the grounded 75 battery 29, through the relay 30, the waiting contact 53, the wiper 49, the upper armature switch of relay 38 and its normal follow-up contact, the waiting contact 45, the wiper 40, the armature switch of the relay 34 next 80 adjacent to its windings, the contact then engaged by this armature switch, to the grounded right hand coil of the relay 34 which is desirably of twenty-five hundred ohms resistance. When the relay 30 was 85 energized the relay 32 and the resistance 31 were excluded from circuit at the left hand normally follow-up contact of the lower armature switch of relay 30, a second gap in the circuit of the motor magnet 37 being established at the left hand armature switch in the relay 32 and the circuit for the left hand winding of the relay 34 being broken at the right hand armature switch of relay 32 whereby the wipers 49, 50 and 51 of other 90 calling line seeking switches will not remain in engagement with waiting contacts that belong to the calling line whose connection is being described. The armature switch of the relay 34 second to the right of its windings 95 is included in circuit that contains the grounded battery 29, the relay 30, one side of the calling line, the telephone receiver and transmitter of the calling line, the magnet 22 at the calling station, the arm 6 in the position to which it has been adjusted by the calling subscriber, the other side of the calling line, the lower armature switch of relay 30, the alternate contact of this armature switch, the waiting contact 54, the 100 wiper 50, the lowermost armature switch of relay 38 and its normal contact, the waiting contact 46, the wiper 41, the said armature switch of the relay 34 and its contact, the relay 56, of say two hundred fifty ohms resistance, and the left hand grounded armature switch of the relay 57 and its contact. The relay 56 thereupon establishes an obvious circuit for the motor magnet 53 of a setting up switch. The circuit of magnet 105 56 is controlled by the switch arm 6 and the circuit of this magnet is therefore broken as the arm 6 is moved toward its normal position which is illustrated. The movement of this switch arm toward its normal position 110

115

120

125

130

was commenced when the circuit, previously traced, was established through the magnet 22 and relay 56. The switch arm 6, in moving to normal, will interrupt the circuit including the magnet 22 and relay 56 but as the magnet 22 is slow to release, the disengaged position of the detent 18 will not be interfered with but the relay 56 which is quick to respond will open and close the circuit for the motor magnet 58 of a setting up switch causing the wipers 59, 60 and 61 to move into connection with a set of waiting contacts 62, 63, 64 individual to the thousands group of link connectors, one of which is to be employed in the established connection, the different sets of waiting contacts 62, 63, 64 being individual to different thousands groups of link connectors, while the wipers 59, 60 and 61 of each setting up switch (there being sufficient of these switches for the traffic of the system) having access to all of the sets of contacts 62, 63 and 64 in the system. The wipers 59, 60 and 61 have been brought into engagement with the desired set of waiting contacts 62, 63 and 64 when the arm 6 has reached the contact button next preceding the normal contact button in the set 14 that is engaged by the arm 6 to continue one of the calling line sides to the contact arm 7. The arm 6 is held at the point preceding its final position by the stop 26 until the magnet 22 is deenergized, a result which occurs when the desired group of thousands has been found by the setting up device having the wipers 59, 60 and 61 and which result is due to the energization of the relay 57 then occurring, the armature switch of this relay opening the circuit for the magnet 22 whereafter the stop 26 is pulled into register with a recess in the arm 6 so that this arm may be brought to normal position in extending its telephone line side into connection with the switch arm 7.

45. A primary master switch A and a secondary master switch B are individual to each other and each is common to a thousands group of link connectors. The primary master switch A has wipers 65, 66 which are adapted to travel over sets of waiting contacts 67, 68 that are individual to each pair of waiting contacts 62, 63. The wipers 59, 60 and 61 are stepped into engagement by the operation of the arm 6 with the desired set of waiting contacts 62, 63 and 64 irrespective of the position of the wipers 65, 66. If the wipers 65, 66 are being employed in establishing another connection the wipers 59, 60 and 61 will remain in the position to which they have been brought waiting for the release of the wipers 65, 66 from their previous employment whereafter these wipers 65, 66 will be stepped around until they engage the waiting contacts 67, 68 that are now connected

with the wipers 59 and 60, the wipers 59, 60 and 61 being permitted to remain as long as need be in the positions to which they have been brought while waiting for the release of the wipers 65, 66 due to the automatically determined delay of the movement of the switch arm 6 to its final and normal position. If the wipers 65 and 66 are not in engagement with the selected waiting contacts 67 and 68 these wipers are brought into such engagement, when released from their previous employment, due to the deenergization of the relay 69 that occurs, in a manner to be stated, when the wipers 65 and 66 are relieved of the previous employment whereupon the left hand armature switch of relay 69 which is common to the various waiting contacts 64 establishes a circuit for the motor magnet 70 of the primary master switch, which circuit includes the grounded battery 29, the interrupter 33, the wiper 61, the waiting contact 64 engaged thereby, the left hand armature switch of the relay 69, the motor magnet 70, the left hand armature switch of relay 71 and its grounded contact. When the wipers 65 and 66 have been brought into engagement with the selected waiting contacts 67 and 68, the circuit of the motor magnet 70 is opened owing to the establishment of a circuit including the grounded battery 29, the relay 69, the wiper 66, the selected waiting contact 68, the selected waiting contact 63, the wiper 60 and the grounded relay 57, this relay 57 being at this time energized to open the circuit of the magnet 22 for the purpose previously described. Battery being now removed at the armature switch of relay 57 from the side of the calling line that includes the switch arms 6 and 7, the magnet 23 cannot be operated to permit the arm 7 to move toward normal until an idle link connector in the selected thousands group has been constituted a continuation of the calling line. The secondary master switch B has wipers 72, 73, 74, 75 and 76 which normally rest in engagement with some set of waiting contacts 77, 78, 79, 80 and 81 that pertain to an idle link connector in the thousands group of link connectors to which this switch B is common, these wipers being adapted for connection with any of such sets of waiting contacts 77, 78, 79, 80 and 81 belonging to the different link connectors in such thousands group. The switch B, when idle, is thus in position to take part in establishing the connection of an idle link connector in the selected thousands group with the link connector having the wipers 49, 50 and 51 that engage the waiting contacts 53, 54 and 55 of the calling line.

Assuming the wipers 72 to 76 to be at rest in engagement with a set of waiting contacts

77 to 81 and assuming that the wipers 65 and 66 are in connection with the selected waiting contacts 62, and 63, a circuit is established for the motor magnet 82 pertaining to the link connector in the thousands group which is to constitute a continuation of the calling line, the different link connectors of this group having such a motor magnet, which motor magnets are thus common to the secondary master switch B, the circuit for this motor magnet 82 including the grounded battery 29, the interrupter 33, the right hand armature switch of the relay 69, the second armature switch to the left of the windings of relay 71, the contact of this armature switch, the wiper 72 of the switch B, the waiting contact 77 engaged by this wiper, the motor magnet 82, and the intermediate grounded armature switch of the relay 83 and the normal contact of this armature switch. The motor magnet 82 will operate the ratchet wheel 84 until the wipers 85, 86 carried by this ratchet wheel are engaged with the waiting contacts 87, 88 that are complementary respectively to the wipers 49 and 50 that are connected with the calling line. When the wipers 85 and 86 thus engage the waiting contacts 87 and 88, the circuit of the motor magnet 82 is opened at the second armature switch to the left of the windings of the relay 71 due to the establishment of a circuit for this relay traceable from the battery 89, the extreme right hand armature switch of relay 34 and its alternate contact, the wiper 42, the waiting contact 47, the lower winding of relay 38, the waiting contact 88, the wiper 86, the lowermost armature switch of relay 83 and its normal contact, the waiting contact 79, the wiper 74, the left hand winding of the relay 71 (which may be of one hundred ohms resistance) the armature switch next adjacent the windings of relay 71, the normal follow-up contact of this armature switch, the wiper 65, the waiting contact 67, the waiting contact 62, the wiper 59, the switch spring 90 now engaging its contact, the release magnet 91, back to the battery 89 whereby the wipers 85, 86 of the actuated motor magnet 82 are permitted to remain in connection with the waiting contacts 87, 88 that are connected with the calling line. The release magnet 91 being included in the circuit just traced, withdraws the actuating pawl of the motor magnet 58 from engagement with the ratchet wheel 92 that carries the wipers 59, 60 and 61 to permit this ratchet wheel to be restored to normal, the ratchet wheel carrying with it the wipers 59, 60 and 61 to normal, the switch spring 90 again being removed from engagement with its waiting contact so that the first setting up switch is restored to normal and in condition to be employed in establishing another connection. The waiting contacts 87 and 88 of the first link connectors

having the wipers 49, 50 and 51 are multiplied in the presence of the wipers 85 and 86 of the selector switches pertaining to the thousands group that have been selected whereby each selector switch having the 70 wipers 85, 86 has access to said sets of waiting contacts 87 and 88. A locking circuit is now established for relay 71 which is traceable from the grounded battery 29, the winding of relay 30 of the calling line, the waiting contact 53 of the calling line, the wiper 49 engaging the waiting contact 53, the uppermost armature switch of the relay 38 now pertaining to the calling line, the right hand alternate contact of this armature switch, 75 the employed waiting contact 87, the wiper 85 engaging this waiting contact, the uppermost armature switch of relay 83 and its normal follow-up contact, the waiting contact 78 of the switch B, the wiper 73 engaging this waiting contact, the right hand armature switch of the relay 71 that is next adjacent the windings of this relay, the contact of this armature switch, to the grounded right hand coil of the relay 71 which may 80 be of twenty five hundred ohms resistance. The locking circuit is also established for the relay 38 traceable from the grounded battery 29, through the upper winding of relay 38, the uppermost armature switch of 95 this relay and its two alternate contacts, the employed waiting contact 87, the employed wiper 85, the uppermost armature switch of relay 83 and its normal follow-up contact, the waiting contact 78, the wiper 73, thence 100 by the two previously traced connections to the right hand grounded coil of the relay 71. The top and bottom armature switches of the relay 38 are thus maintained in connection with their alternate contacts whereby 105 the calling line sides are extended into connection with the waiting contacts 87 and 88 and therethrough in connection with the top and bottom armature switches of the relay 83. The intermediate armature switch of 110 the relay 38, when attracted, establishes a circuit for the motor magnet 93 of the master switch having the wipers 35, 39, 40, 41, 42 and 43 whereby this motor magnet operates the ratchet wheel 94 to bring these 115 wipers into engagement with a set of waiting contacts pertaining to another but idle link connector of the group to which this master switch is common, it being understood that these wipers are adapted to pass 120 over the different sets of such waiting contacts individual to a group of link connectors to which such master switch is common. This master switch and its associate equipment are thus restored to normal to be 125 adapted for use in effecting another connection between calling and desired lines. The elements 7, 19, 23 and 27 at the calling substation are now in cooperative relation with the setting up switch C, the primary master 130

switch D and the secondary master switch E which pertain to the link connectors in the selected hundreds group whereby an idle link connector in such selected hundreds group is connected with the employed link connector in the thousands group whereby the calling line is extended into connection with such employed link connector in the selected hundred group, link connectors of such hundreds group being illustrated at F whereafter the elements 8, 20, 24 and 28 at the calling substation are now in coöperative relation with the setting up switch G, the primary master switch H and the secondary master switch I which pertain to the link connectors in the selected tens group whereby an idle link connector in such selected tens group is connected with the employed link connector in the hundreds group where- 10 by the calling line is extended into connection with such employed link connector in the selected tens group, link connectors of such tens group being illustrated at K whereafter the elements 9, 21, and 25 at the calling substation are now in coöperative relation with the setting up switch L. The elements of the hundreds setting up switch at the calling substation and which include parts marked 7, 11, 15, 19, 23 and 27 are co- 20 operatively associated with elements which are similar in function and operation to the elements that coöperate with the thousands setting up switching device at the calling station which includes the parts marked 6, 10, 14, 18, 22 and 26, the elements which co- 30 operate with said hundreds setting up switch that are similar in function and operation to the elements that coöperate with said thousands setting up switch having similar characters of reference but with a prime mark added to each. The elements of the tens setting up switch at the calling substation and which include parts marked 8, 12, 16, 20, 24 and 28 are coöperatively associated with 40 elements which are similar in function and operation to the elements that coöperate with the thousands setting up switching device at the calling station, the elements which coöperate with said tens setting up switch that are similar in function and operation to the elements that coöperate with said thousands setting up switch having similar characters of reference but with the exponent 2 added to each. The elements 50 of the units setting up switch at the calling substation and which include parts marked 9, 13, 17, 21 and 25 are coöperatively associated with elements which are similar in function and operation to the elements that coöperate with the thousands setting up switching devices at the calling station, the elements which coöperate with said units setting up switch that are similar in function and operation to the elements that co- 60 operate with said thousands setting up

switch having similar characters of reference but with the exponent 3 added to each. The units setting up switching device at the calling station has its arm 9 unprovided with any adjustable stop, having only a rigid stop 9¹ to prevent the arm from passing by its normal position in its clockwise movement, there being no occasion to delay the restoration of the arm 9 to its normal position inasmuch as this arm is to operate immediately to associate the desired line with the calling line. The wiper 95 carried by the ratchet wheel 92² is stepped around as a consequence of the operation of the units setting up switching device at the calling station until it engages a waiting contact 96 individual to the desired line whereupon a circuit is established through the motor magnet 97 to cause this motor magnet to operate its ratchet wheel 98 to bring the wipers 99, 100 carried by this ratchet wheel into engagement with the waiting contacts 101, 102 of the desired line. The circuit established for the motor magnet 97 is traceable from the grounded battery 29, the interrupter 33, the switch spring 103 and the contact initially engaged thereby when the ratchet wheel 92² was first operated, the wiper 104 of the secondary master switch I, the waiting contact engaged by this wiper, the motor magnet 97, the intermediate armature switch of the relay 83² and its right hand normal follow-up contact, to ground. When the wipers 99, 100 engage the waiting contacts 101, 102 that belong to the same line that has the waiting contact 96 engaged by the wiper 95, the circuit of the motor magnet 97 will be opened at the right hand normal contact of the intermediate armature switch of the relay 83² if the desired line is idle whereby the wipers 99, 100 will be arrested in engagement with the desired waiting contacts 101, 102, circuit for the relay 83² thereupon being established, this circuit being traceable from the battery 89², the extreme right hand armature switch of the relay 71², the alternate contact of this armature switch, the wiper 75², the waiting contact 80² engaged thereby, the lowermost winding of the relay 83², the right hand armature switch of relay 105 and its normal contact, the lowermost armature switch of relay 106 and its normal follow-up contact, the wiper 100, the waiting contact 102 engaged thereby, the upper switch of the desired subscriber's relay 30 and its then engaged contact, assuming that the desired line is idle, the engaged waiting contact 96, the wiper 95 engaging this waiting contact, the switch 90² and its then engaged contact, the release magnet 91², back to the battery 89² whereupon the release magnet 91² is energized to release the ratchet wheel 92² to permit the wiper 95 to be restored to normal and to permit the switch springs 90² and 13

the switch spring 103 to be separated from their contacts whereby the setting up switching device L is restored to normal in readiness to be employed in establishing another connection. It is understood that the setting up switching devices at the exchange that may be restored to normal are not adapted to be used in setting up other connections until their controlling master switches have been stepped off of the waiting contacts with which they are connected. If the desired line is busy the wipers 99 and 100 will continue in operation either until the calling subscriber restores his telephone upon its switch hook or until the previously busy desired subscriber restores his telephone upon its switch hook whereupon the relay 30 of such desired line will be de-energized to permit its upper armature switch to engage its contact whereby the wipers 99, 100 may become connected with the desired line. When the relay 83² is energized it establishes circuit through the left hand winding of the relay 105 which circuit is traceable from the grounded intermediate armature switch of the relay 83², the alternate contact of this armature switch, the left hand winding of the relay 105, having say a resistance of two hundred fifty ohms, the lowermost armature switch of relay 83² and its alternate contact, the wiper 86², the waiting contact 88², thence by obvious connections over both sides of the calling line to the grounded battery 29 by way of the winding of relay 30, the upper windings of relays 38, 83, 83¹ and 83², these relay windings being thus in parallel relation. This circuit, including its multiple paths, constitutes a holding circuit for the various relay windings included therein. The left hand armature switch of the relay 105 now establishes a circuit for the motor magnet 93³ to move the wipers of the master switch I from the waiting contacts engaged thereby into connection with the succeeding set of waiting contacts connected with an idle link connector in the tens group to which the switch I is common. The right hand armature switch and its alternate contact establish a circuit for the lower winding of relay 106 whereby the ringing generator 107 is included in circuit with the signal bell at the desired station. This lower winding of the relay 106 may be of twenty five hundred ohms' resistance so that the relay 106 will not be operated when the current from generator 107 finds a path through the comparatively high resistance signal bell at the desired station. When the called party responds current from the generator 107 will find a path through the low resistance telephone bridge at the called station so that the ringing current flowing through the lower winding of the relay 106 will be sufficiently increased to energize this relay which thereupon establishes a locking circuit for itself traceable from the grounded battery 29, the upper winding of the relay 106, the intermediate armature switch of this relay and its then engaged contact, the intermediate armature switch of the relay 83² and its alternate contact, to ground. The top and bottom armature switches of the relay 106 now serve to engage their alternate contacts to continue the calling line 75 sides into connection with the wipers 99 and 100 whereby telephonic connection between the calling and called stations is complete. Talking current is supplied to the called station by a circuit traceable from the 80 grounded battery 29, the relay 30 of the called line, both sides of the called line, the lower armature switch of the relay 30 of the called line, and its now engaged alternate contact, the waiting contact 102 of the called line, the wiper 100 engaging this waiting contact, the lowermost armature switch of the relay 106 and its alternate contact, the right hand winding of relay 105, the intermediate armature switch of relay 83² and 85 its alternate contact to ground, the relay 30 of the called line being at the same time energized to prevent it from being selected by another calling line while telephonically connected with the first calling line. It 90 should be observed that the relay 30 of the called line is maintained energized while calling current is passing over the called line by a circuit traceable from the grounded battery 29, the winding of said relay 30, the 100 waiting contact 101 of the called line, the wiper 99 engaging this waiting contact, the uppermost armature switch of the relay 106 and its normal contact, the intermediate armature switch of the relay 83² and its alternate contact to ground whereby ringing current will flow through the lower armature switch of the relay 30 of the called line and its alternate contact. When the subscribers are through conversation they restore their telephone receivers to their switch hooks whereupon their relays 30 are de-energized, the relay 105 is de-energized, and the relays 38, 83, 83¹ and 83² are de-energized causing the equipment to be 105 restored to normal, it being understood that, in the embodiment of the invention shown, the wipers of the various selector switches individual to the link connectors may remain in engagement with the waiting contacts engaged thereby until another connection is being established though the invention is not to be restricted to this characteristic. The calling line extending switching devices are illustrated as including distinct 125 electro-magnets 22, 23, 24 and 25 for the sake of simplicity of illustration and the switch arms 6, 7, 8 and 9 are shown as being adapted for direct manual operation, also for the sake of simplicity of illustration, but 130

it will be apparent to those skilled in the art that operating equipment may be employed which is not limited to such characteristics. The delay in the operation of the 5 calling line extending switching devices at the calling stations is desirably secured, particularly in the embodiment of the invention herein shown, by providing a plurality of switch arms 6, 7 and 8 but this is a characteristic to which the invention is not to be 10 limited. It is also apparent from the description of the preferred embodiment of the invention given that there are many features of the invention that are not to be 15 restricted to those systems by which connections may be established by apparatus at a calling station with desired stations and the invention is not therefore to be limited to systems that are purely automatic, nor is the 20 system to be limited to one in which the calling stations are substations of subscribers' lines that extend to an exchange.

It is obvious that many changes may be 25 made in the preferred embodiment of my invention herein illustrated without departing from the spirit of the invention and I do not therefore wish to be limited to the precise details of construction and circuit arrangement shown and

30 Having thus described my invention I claim as new and desire to secure by Letters Patent the following:—

1. A telephone exchange system including 35 telephone lines extending from substations to an exchange; extensions for such telephone lines adapted for connection therewith in successive order; successively operating electro-magnetic switching devices respectively co-operatively related with the 40 successively related extensions in their order and in the order of operation of said electro-magnetic switching devices and operating in succession for connecting such extensions in successive order with calling telephone lines; successively operating calling line extending 45 switching devices at each of the substations of said telephone lines that are respectively adapted for operative association in the order of their succession with the successively operating electro-magnetic switching devices in the order of succession of the latter; and electro-magnetic means whereby the calling line extending switching devices which succeed the first at a calling station 50 are successively brought into co-operative relation with their line, and operated by the extensions associated with preceding calling line extending switching devices for this purpose when such extensions are connected 55 with the line of such calling line extending switching devices.

2. A telephone exchange system including 60 telephone lines extending from substations to an exchange; extensions for such telephone lines adapted for connection there-

with in successive order; successively operating electro-magnetic switching devices respectively co-operatively related with the successively related extensions in their order and in the order of operation of said 70 electro-magnetic switching devices and operating in succession for connecting such extensions in successive order with calling telephone lines; successively operating calling line extending switching devices at each 75 of the substations of said telephone lines that are respectively adapted for operative association in the order of their succession with the successively operating electro-magnetic switching devices in the order of succession of the latter; and electromagnetically controlled devices whereby the calling line extending switching devices which succeed the first at a calling station, and to which succeeding calling line extending 80 switching devices said electromagnetically controlled devices are individual, are successively brought into co-operative relation with their line, these electro-magnetically controlled devices being respectively operated in succession by the extensions associated with preceding calling line extending switching devices for this purpose when such extensions are connected with the line of such calling line extending switching devices.

3. A telephone exchange system including 90 telephone lines extending from substations to an exchange; extensions for such telephone lines adapted for connection therewith in successive order; successively operating electro-magnetic switching devices respectively co-operatively related with successively related extensions in their order and in the order of operation of said electro-magnetic switching devices and operating in succession for connecting such extensions in successive order with calling telephone lines; calling line extending switching devices at stations of said telephone lines for 100 effecting the operation of said electro-magnetic switching devices successively in their order; and means for preventing the effective operation of said calling line extending switching devices to connect succeeding extensions with calling lines until preceding extensions have been connected with calling lines, and operated by extensions connected with the calling lines to permit them to operate to connect succeeding extensions with 110 the preceding extensions.

4. A telephone exchange system including 115 telephone lines whose stations, when calling, are to have telephone line extensions connected therewith; extensions for such telephone lines adapted for connection therewith in successive order; successively operating electro-magnetic switching devices respectively co-operatively related with the successively related extensions in their order 125

and in the order of operation of said electro-magnetic switching devices and operating in succession for connecting such extensions in successive order with calling telephone lines; successively operating calling line extending switching devices at each of the substations of said telephone lines that are respectively adapted for operative association in the order of their succession with the successively operating electro-magnetic switching devices in the order of succession of the latter; and electro-magnetic means whereby the calling line extending switching devices which succeed the first at a calling station are successively brought into co-operative relation with their line and operated by the extensions associated with preceding calling line extending switching devices for this purpose when such extensions are connected with the line of such calling line extending switching devices.

5. A telephone exchange system including telephone lines whose stations, when calling, are to have telephone line extensions connected therewith; extensions for such telephone lines adapted for connection therewith in successive order; successively operating electro-magnetic switching devices respectively co-operatively related with the successively related extensions in their order and in the order of operation of said electro-magnetic switching devices and operating in succession for connecting such extensions in successive order with calling telephone lines; successively operating calling line extending switching devices at each of the substations of said telephone lines that are respectively adapted for operative association in the order of their succession with the successively operating electro-magnetic switching devices in the order of succession of the latter; and electro-magnetically controlling devices whereby the calling line extending switching devices which succeed the first at a calling station, and to which succeeding calling line extending switching devices said electro-magnetically controlled devices are individual, are successively brought into co-operative relation with their line, these electro-magnetically controlled devices being respectively operated in succession by the extensions associated with preceding calling line extending switching devices for this purpose when such extensions are connected with the line of such calling line extending switching devices.

6. A telephone exchange system including telephone lines extending from substations to an exchange; setting up switches adapted for operation by calling stations; primary master switches adapted to be selected by the setting up switches and which in turn are adapted to select employed setting up switches; secondary master switches co-operatively related with the primary master

switches and co-operatively related by said primary master switches with employed setting up switches; a plurality of sets of calling line extensions to the extensions of each of which sets a secondary master switch is common, whereby said secondary master switches are enabled to associate idle telephone line extensions of selected sets with calling lines; and electro-magnetic switching mechanism for connecting an idle extension of a selected set with a calling line, there being calling station equipment for operating said electro-magnetic switching mechanism and co-operatively associated with such electro-magnetic switching mechanism by employed setting up, primary master, and secondary master switches.

7. A telephone exchange system including telephone lines extending from substations to an exchange; setting up switches adapted for operation by calling stations; primary master switches adapted to be selected by the setting up switches and which in turn are adapted to select employed setting up switches; secondary master switches co-operatively related with the primary master switches and co-operatively related by said primary master switches with employed setting up switches, each secondary master switch having a primary master switch individual thereto; a plurality of sets of calling line extensions to the extensions of each of which sets a secondary master switch is common, whereby said secondary master switches are enabled to associate idle telephone line extensions of selected sets with calling lines; and electro-magnetic switching mechanism for connecting an idle extension of a selected set with a calling line, there being calling station equipment for operating said electro-magnetic switching mechanism and co-operatively associated with such electro-magnetic switching mechanism by employed setting up, primary master, and secondary master switches.

8. A telephone exchange system including telephone lines extending from substations to an exchange; setting up switches adapted for operation by calling stations; primary master switches adapted to be selected by the setting up switches and which in turn are adapted to select employed setting up switches; secondary master switches co-operatively related with the primary master switches and co-operatively related by said primary master switches with employed setting up switches; a plurality of sets of calling line extensions to the extensions of each of which sets a secondary master switch is common whereby said secondary master switches are enabled to associate idle telephone line extensions of selected sets with calling lines; and electro-magnetic switching devices individual to said extensions for connecting the same with calling lines, there being calling

station equipment for operating said electro-magnetic switching devices and co-operatively associated with such electro-magnetic switching devices by employed setting up, 5 primary master, and secondary master switches.

9. A telephone exchange system including telephone lines extending from substations to an exchange; setting up switches adapted for operation by calling stations; primary master switches adapted to be selected by the setting up switches and which in turn are adapted to select employed setting up switches; secondary master switches coöperatively related with the primary master switches and coöperatively related by said primary master switches with employed setting up switches, each secondary master switch having a primary master switch individual thereto; a plurality of sets of calling line extensions to the extensions of each of which sets a secondary master switch is common whereby said secondary master switches are enabled to associate idle telephone line extensions of selected sets with calling lines; and electro-magnetic switching devices individual to said extensions for connecting the same with calling lines, there being calling station equipment for operating said electro-magnetic switching devices and coöperatively associated with such electro-magnetic switching devices by employed setting up, primary master, and secondary master switches.

35 10. A telephone exchange system including telephone lines extending from substations to an exchange; setting up switches adapted for operation by calling stations; primary master switches adapted to be selected by the setting up switches and which in turn are adapted to select employed setting up switches; secondary master switches co-operatively related with the primary master switches and co-operatively related by 40 said primary master switches with employed setting up switches; a plurality of sets of calling line extensions to the extensions of each of which sets a secondary master switch is common, whereby said secondary master 45 switches are enabled to associate idle telephone line extensions of selected sets with calling lines; electro-magnetic switching mechanism for connecting an idle extension of a selected set with a calling line, there being calling station equipment for operating said electro-magnetic switching mechanism and co-operatively associated with such electro-magnetic switching mechanism by employed setting up, primary master, and 50 secondary master switches; and means whereby each secondary master switch is normally co-operatively related with an idle extension of its set of extensions and is removed from such co-operative relation when 55 60 65 it has been employed to connect an extension.

sion with a calling line and is thereafter brought into coöperative relation with another idle extension.

11. A telephone exchange system including telephone lines extending from substations to an exchange; setting up switches adapted for operation by calling stations; primary master switches adapted to be selected by the setting up switches and which in turn are adapted to select employed setting up switches; secondary master switches coöperatively related with the primary master switches and coöperatively related by said primary master switches with employed setting up switches, each secondary master switch having a primary master switch individual thereto; a plurality of sets of calling line extensions to the extensions of each of which sets a secondary master switch is common, whereby said secondary master switches are enabled to associate idle telephone line extensions of selected sets with calling lines; electro-magnetic switching mechanism for connecting an idle extension of a selected set with a calling line, there being calling station equipment for operating said electro-magnetic switching mechanism and coöperatively associated with such electro-magnetic switching mechanism by employed setting up, primary master, and secondary master switches; and means whereby each secondary master switch is normally coöperatively related with an idle extension of its set of extensions and is removed from such coöperative relation when it has been employed to connect an extension with a calling line and is thereafter brought into coöperative relation with another idle extension.

12. A telephone exchange system including telephone lines extending from substations to an exchange; setting up switches adapted for operation by calling stations; primary master switches adapted to be selected by the setting up switches and which in turn are adapted to select employed setting up switches; secondary master switches co-operatively related with the primary master switches and co-operatively related by said primary master switches with employed setting up switches; a plurality of sets of calling line extensions to the extensions of each of which sets a secondary master switch is common whereby said secondary master switches are enabled to associate idle telephone line extensions of selected sets with calling lines; electro-magnetic switching devices individual to said extensions for connecting the same with calling lines, there being calling station equipment for operating said electro-magnetic switching devices and co-operatively associated with such electro-magnetic switching devices by employed setting up, primary master, and secondary master switches; and means where-

5 by each secondary master switch is normally coöperatively related with an idle extension of its set of extensions and is removed from such coöperative relation when it has been employed to connect an extension with a calling line and is thereafter brought into coöperative relation with another idle extension.

10 13. A telephone exchange system including telephone lines extending from substations to an exchange; setting up switches adapted for operation by calling stations; primary master switches adapted to be selected by the setting up switches, and 15 which in turn are adapted to select employed setting up switches; secondary master switches coöperatively related with the primary master switches and coöperatively related by said primary master switches 20 with employed setting up switches, each secondary master switch having a primary master switch individual thereto; a plurality of sets of calling line extensions to the 25 extensions of each of which sets a secondary master switch is common whereby said secondary master switches are enabled to associate idle telephone line extensions of selected sets with calling lines; electro-magnetic switching devices individual to said 30 extensions for connecting the same with calling lines, there being calling station equipment for operating said electro-magnetic switching devices and coöperatively associated with such electro-magnetic switching devices by employed setting up, primary, and secondary master switches; and means whereby each secondary master switch is normally coöperatively related with an idle extension of its set of 35 extensions and is removed from such coöperative relation when it has been employed to connect an extension with a calling line and is thereafter brought into coöperative relation with another idle extension.

40 14. A telephone exchange system including telephone lines extending from substations to an exchange; primary master switches in seeking relation to calling lines; secondary master switches coöperatively related with the primary master switches; a plurality of sets of calling line extensions to the 45 extensions of each of which sets a secondary master switch is common, whereby said secondary master switches are enabled to associate idle telephone line extensions of selected sets with calling lines; and electro-magnetic switching mechanism for connecting an idle extension of a selected set with a calling line, there being calling station equipment for operating said electro-magnetic switching mechanism and coöperatively associated with such electro-magnetic switching mechanism by employed primary master and secondary master switches.

50 15. A telephone exchange system includ-

ing telephone lines extending from substations to an exchange; primary master switches in seeking relation to calling lines; secondary master switches coöperatively related with the primary master switches, each secondary master switch having a primary master switch individual thereto; a plurality of sets of calling line extensions to the extensions of each of which sets a secondary master switch is common, whereby said secondary master switches are enabled to associate idle telephone line extensions of selected sets with calling lines; and electro-magnetic switching mechanism for connecting an idle extension of a selected set with a calling line, there being calling station equipment for operating said electro-magnetic switching mechanism and coöperatively associated with such electro-magnetic switching mechanism by employed primary master and secondary master switches.

55 16. A telephone exchange system including telephone lines extending from substations to an exchange; primary master switches in seeking relation to calling lines; secondary master switches coöperatively related with the primary master switches; a plurality of sets of calling line extensions to the extensions of each of which sets a secondary master switch is common whereby said secondary master switches are enabled to associate idle telephone line extensions of selected sets with calling lines; and electro-magnetic switching devices individual to said extensions for connecting the same with calling lines, there being calling station equipment for operating said electro-magnetic switching devices and coöperatively associated with such electro-magnetic switching devices by employed primary master and secondary master switches.

60 17. A telephone exchange system including telephone lines extending from substations to an exchange; primary master switches in seeking relation with calling lines; secondary master switches coöperatively related with the primary master switches, each secondary master switch having a primary master switch individual thereto; a plurality of sets of calling line extensions to the extensions of each of which sets a secondary master switch is common whereby said secondary master switches are enabled to associate idle telephone line extensions of selected sets with calling lines; and electro-magnetic switching devices individual to said extensions for connecting the same with calling lines, there being calling station equipment for operating said electro-magnetic switching devices and coöperatively associated with such electro-magnetic switching devices by employed primary master and secondary master switches.

65 18. A telephone exchange system includ-

- ing telephone lines extending from substations to an exchange; primary master switches in seeking relation to calling lines; secondary master switches coöperatively related with the primary master switches; a plurality of sets of calling line extensions to the extensions of each of which sets a secondary master switch is common, whereby said secondary master switches are enabled
- 5 10 to associate idle telephone line extensions of selected sets with calling lines; electro-magnetic switching mechanism for connecting an idle extension of a selected set with a calling line, there being calling station
- 15 equipment for operating said electro-magnetic switching mechanism and coöperatively associated with such electro-magnetic switching mechanism by employed primary master and secondary master switches; and
- 20 means whereby each secondary master switch is normally coöperatively related with an idle extension of its set of extensions and is removed from such coöperative relation when it has been employed to
- 25 connect an extension with a calling line and is thereafter brought into coöperative relation with another idle extension.
19. A telephone exchange system including telephone lines extending from substations to an exchange; primary master switches in seeking relation to calling lines; secondary master switches coöperatively related with the primary master switches, each secondary master switch having a pri-
- 30 35 40 45 50 55 60 65 70 75 80 85 90 95 100 105 110 115 120 125 130
- ary master switch individual thereto; a plurality of sets of calling line extensions to the extensions of each of which sets a secondary master switch is common, whereby said secondary master switches are enabled to associate idle telephone line extensions of selected sets with calling lines; electro-magnetic switching mechanism for connecting an idle extension of a selected set with a calling line, there being calling station equipment for operating said electro-magnetic switching mechanism and coöperatively associated with such electro-magnetic switching mechanism by employed primary master and secondary master switches; and
- means whereby each secondary master switch is normally coöperatively related with an idle extension of its set of extensions and is removed from such coöperative relation when it has been employed to connect an extension with a calling line and is thereafter brought into coöperative relation with another idle extension.
20. A telephone exchange system including telephone lines extending from substations to an exchange; primary master switches in seeking relation to calling lines; secondary master switches coöperatively related with the primary master switches; a plurality of sets of calling line extensions to the extensions of each of which sets a sec-

ondary master switch is common whereby said secondary master switches are enabled to associate idle telephone line extensions of selected sets with calling lines; electro-magnetic switching devices individual to said extensions for connecting the same with calling lines, there being calling station equipment for operating said electro-magnetic switching devices and coöperatively associated with such electro-magnetic switching devices by employed primary master and secondary master switches; and means whereby each secondary master switch is normally coöperatively related with an idle extension of its set of extensions and is removed from such coöperative relation when it has been employed to connect an extension with a calling line and is thereafter brought into coöperative relation with another idle extension.

21. A telephone exchange system includ- 90 95 100 105 110 115 120 125 130

ing telephone lines extending from substations to an exchange; primary master switches in seeking relation to calling lines; secondary master switches coöperatively re- 90

lated with the primary master switches, each secondary master switch having a primary master switch individual thereto; a plurality of sets of calling line extensions to the extensions of each of which sets a secondary master switch is common whereby said secondary master switches are enabled to associate idle telephone line extensions of selected sets with calling lines; electro-magnetic switching devices individual to said extensions for connecting the same with calling lines, there being calling station equipment for operating said electro-magnetic switching devices and coöperatively associated with such electro-magnetic switching devices by employed primary master and secondary master switches; and means whereby each secondary master switch is normally coöperatively related with an idle extension of its set of extensions and is removed from such coöperative relation when it has been employed to connect an extension with a calling line and is thereafter brought into coöperative relation with another idle extension.

22. A telephone exchange system includ- 115 120 125 130

ing telephone lines extending from substations to an exchange; extensions for such telephone lines adapted for connection therewith in successive order; successively operating electro-magnetic switching devices respectively coöperatively related with the successively related extensions in their order and in the order of operation of said electro-magnetic switching devices and operating in succession for connecting such extensions in successive order with calling telephone lines; successively operating calling line extending switching devices at each of the substations of said telephone lines that are re-

spectively adapted for operative association in the order of their succession with the successively operating electro-magnetic switching devices in the order of succession of the latter; and electro-magnetic means whereby a calling line extending switching device which succeeds the first at a calling station is brought into coöperative relation with its line and is operated by the extension associated with the preceding calling line extending switching device for its purpose when such extension is connected with the calling line.

23. A telephone exchange system including telephone lines extending from substations to an exchange; extensions for such telephone lines adapted for connection therewith in successive order; successively operating electro-magnetic switching devices respectively coöperatively related with the successively related extensions in their order and in the order of operation of said electro-magnetic switching devices and operating in succession for connecting such extensions in successive order with calling telephone lines; successively operating calling line extending switching devices at each of the substations of said telephone lines that are respectively adapted for operative association in the order of their succession with the successively operating electro-magnetic switching devices in the order of succession of the latter; and electro-magnetic means whereby a calling line extending switching device which succeeds the first at a calling station, is brought into coöperative relation with its line when said first switching device has performed its function.

24. A telephone exchange system including telephone lines extending from substations to an exchange; extensions for such telephone lines adapted for connection therewith in successive order; successively operating electro-magnetic switching devices respectively coöperatively related with the successively related extensions in their order and in the order of operation of said electro-magnetic switching devices and operating in succession for connecting such extensions in successive order with calling telephone lines; successively operating calling line extending switching devices at each of the substations of said telephone lines that are respectively adapted for operative association in the order of their succession with the successively operating electro-magnetic switching devices in the order of succession of the latter; and means whereby a calling line extending switching device which succeeds the first at a calling station is brought into coöperative relation with its line when said

first switching device has performed its function.

25. A telephone exchange system including telephone lines extending from subscribers' stations to an exchange; link connectors for uniting lines in conversation; electro-magnetic connector switches including traveling wipers for uniting desired lines with said link connectors; and means pertaining to the telephone lines and governed thereby when their lines are to be called for continuing the wiper of said connector switches in operation to prevent them from connecting the link connectors with desired lines when such lines are previously busy and for thereafter stopping the wiper of said connector switches to connect said link connectors with previously busy desired lines when the receivers at their stations have been restored upon their switch hooks.

26. A telephone exchange system including telephone lines extending from subscribers' stations to an exchange; extensions for such telephone lines; link connectors for uniting calling lines with said extensions; electro-magnetic connector switches including traveling wipers for uniting desired extensions with said link connectors; and means pertaining to the telephone line extensions and governed thereby when previously taken for use for continuing the wiper of said connector switches in operation to prevent them from connecting desired link connectors therewith, and for thereafter stopping the wiper of said connector switches to connect said link connectors with previously busy extensions when released from their previous use.

27. A telephone exchange system including telephone line extensions; electro-magnetic connector switches including traveling wipers for including desired extensions in telephonic circuits; and means pertaining to the telephone line extensions and governed thereby when previously taken for use for continuing the wiper of said connector switches in operation to prevent them from connecting desired extensions in telephone circuits, and for thereafter stopping the wiper of said connector switches to include desired extensions in telephonic circuits when such extensions are released from their previous use.

In witness whereof, I hereunto subscribe my name this thirty first day of March A. D., 1913.

ELMER R. CORWIN.
